UNITED STATES PATENT OFFICE

JAMES H. HICKS, OF CHICAGO, ILLINOIS

DESIGN FOR A BOX

Application filed September 17, 1931. Serial No. 41,132. Term of patent 14 years.

To all whom it may concern:

Be it known that I, JAMES H. HICKS, a citizen of the United States, residing at Chicago, in the county of Cook and State of Illinois, have invented a new, original, and ornamental Design for a Box, of which the following is a specification, reference being had to the accompanying drawings, forming a part thereof.

Fig. 2 is a bottom plan view of the box.

I claim:

The ornamental design for a box substantially as shown.

JAMES H. HICKS.
